United States Patent Office.

LEONARD TILTON, OF BROOKLYN, E. D., NEW YORK.

Letters Patent No. 80,241, dated July 21, 1868.

IMPROVEMENT IN WOOD-SPLITTING MACHINES.

The Schedule referred to in these Letters Patent and making part of the same.

TO ALL WHOM IT MAY CONCERN:

Be it known that I, LEONARD TILTON, of Brooklyn, E. D., in the county of Kings, and State of New York, have invented a new and improved Machine for Splitting Wood; and I do hereby declare that the following is a full, clear, and exact description thereof, which will enable others skilled in the art to make and use the same, reference being had to the accompanying drawings, forming part of this specification.

This invention relates to a new and improved machine for splitting wood, and it consists in the employment or use of fixed cutters, a reciprocating hopper, and a vibrating or other moving bed, all arranged to operate in the manner substantially as and for the purpose set forth.

In the accompanying sheet of drawings—

Figure 1 is a longitudinal vertical section of my invention, taken in the line *x x*, fig. 2.

Figure 2, a transverse vertical section of the same, taken in the line *y y*, fig. 1.

Similar letters of reference indicate corresponding parts.

A represents a rectangular frame, having at its top two parallel horizontal rods, *B B*, which serve as ways or guides for a reciprocating box, *C*, having two vertical partitions, *a a*, within it, to form two hoppers, *D D*, in which the wood to be split is placed.

On the top of the box *C*, between the two partitions *a a*, there is placed transversely a rock-shaft, *E*, having a pendent plate, *b*, to the lower end of which a bed, *F*, is attached, said bed being of V-shape in its transverse section, as shown clearly in fig. 2.

The lower part of the plate *b* has a journal, *c*, extending from it, one from each side, and these journals are fitted in fixed bearings, *d*, on the guide-rods *B B*.

The box *C* is connected by rods *G G* to cranks *H H*, at the ends of a driving-shaft, *I*, at one end of the frame *A*, and by turning the shaft *I* a reciprocating motion is given the box *C*, and at the same time a vibrating or oscillating movement given the bed *F*, so that the latter will be moved first under one hopper, and then under the other, the bed working on the journals *c* as centres.

J J' and *K K'* are fixed cutters, secured firmly to cross-bars *L L*, which are permanently secured on the guide-rods *B B*. These cutters are all of V-form, as shown in fig. 2, the hollow or concave of the upper cutters *J K* being uppermost, and the hollow or concave of the lower cutters *J' K'* being undermost, the angles of the upper and lower cutters being in close proximity to each other.

The ends of the box *c* have V-shaped slots made in them, to allow the cutters to pass through, and the upper cutters are somewhat shorter than the lower ones *J' K'*; as shown in fig. 1.

As the box *C* is moved, first in one direction and then in the other, one pair of cutters is made, at the completion of one stroke of the box, to extend entirely across one hopper, *D*, and at the completion of the succeeding stroke, the other pair of cutters is made to extend entirely across the other hopper. The hoppers *D D* are filled with wood, the pieces being cut of a uniform length. The pieces of wood, by the movement of the box *C*, are split, in consequence of being forced against the cutters, the upper cutters *J K* not extending entirely through the wood, and consequently only checking the same, the complete cuts being given by the lower cutters *J' K'*, which sever the split portions entirely from the pieces or blocks.

The reverse positions of the cutter cause the wood to be split of the required degree of fineness, as the cuts of the lower cutters cross the checks of the upper cutters at right angles. While the cuts are being made, the lower pieces of wood are supported by the lower cutters *J' K'*, the wood in each hopper, when wound off from the cutters, being sustained by the bed *F*, which, by its oscillating movement, is made to pass from underneath the hopper that is being shoved against the cutters, and underneath the upper that is being moved off from them. This will be understood by referring to fig. 1.

I would remark that one hopper, *D*, and one pair of cutters may be used for small machines, to work with but little power, but in a quantity of cases the two hoppers and two pairs of cutters would be the most durable machine.

I do not claim separately the cutters J J', K K', for they have been previously used, although arranged to operate entirely different from the way herein shown and described, the cutter not being fixed; but

I do claim as new, and desire to secure by Letters Patent—

1. The bed F, made V-shaped in its cross-section, and provided with the journals c and shank b, said bed being arranged to oscillate in connection with the rock-shaft F, so as to alternately close the bottoms of the hoppers D D, substantially as herein shown and described, for the purpose specified.

2. The arrangement of the V-shaped cutters J J', K K', with relation to the slotted hopper D and oscillating bed F, as herein described, for the purpose specified.

The above specification of my invention signed by me, this 28th day of April, 1868.

LEONARD TILTON.
